UNITED STATES PATENT OFFICE.

PIERRE E. GUERIN, OF NEW YORK, N. Y.

DESIGN FOR A LAMP-STANDARD.

SPECIFICATION forming part of Design No. 16,747, dated June 22, 1886.

Application filed March 4, 1886. Serial No. 194,069. Term of patent 3½ years.

To all whom it may concern:

Be it known that I, PIERRE E. GUERIN, of the city, county, and State of New York, have invented a new and original Design for Ornamental Lamp-Standards, of which the following is a full, clear, and exact description, reference being had to the accompanying photograph, making part of this specification, in which photograph a perspective view of my new ornamental lamp-standard is shown.

The leading feature of my design consists in a lamp-standard having a spiral groove containing leaf ornaments in relief. Another feature of the design is a spiral groove in the socket on the capital of the lamp-standard; and another feature consists of the collars on the lamp-standard, all as will be further set forth hereinafter.

A is a lamp-standard. B is a spiral groove in the same, and C leaf ornaments in relief in said spiral groove.

D is a collar at about the middle of the lamp-standard, the top of the collar being tapered from the edges toward the lamp-standard. E is a smaller spirally-ribbed collar below the collar D.

F is a capital of the renaissance style.

G is a socket having a central leg on the top of the capital. The outer surface of the sock-

et is ornamented with spiral grooves and leaf ornaments in said grooves extending the length of the same.

H is an acorn ornament or drop at the center of the base, and J are four legs constituting the base, which legs are ornamented in the renaissance style.

Having thus described my design, I claim as new and desire to secure by Letters Patent—

1. The design for an ornamental lamp-standard herein shown and described, the same consisting of the lamp-standard rising from the base and legs, and having a spiral groove and a leaf ornament in the same, substantially as shown and described. 40

2. The herein-described design for ornamental lamp-standards, consisting of the lamp-standard having a spiral groove, a leaf ornament in the groove, and the base and legs, and a collar at the middle of the lamp-standard, substantially as shown and described. 45

In testimony that I claim the foregoing as my invention I have signed it this 25th day of February, 1886.

PIERRE E. GUERIN.
